UNITED STATES PATENT OFFICE.

ELMER A. EKLUND, OF SPENCER, SOUTH DAKOTA.

ROTARY VALVE FOR INTERNAL-COMBUSTION ENGINES.

1,286,260.

Specification of Letters Patent.

Patented Dec. 3, 1918.

Application filed October 29, 1917. Serial No. 199,049.

To all whom it may concern:

Be it known that I, ELMER A. EKLUND, a citizen of the United States, residing at Spencer, in the county of McCook and State 5 of South Dakota, have invented certain new and useful Improvements in Rotary Valves for Internal-Combustion Engines, of which the following is a specification, reference being had to the accompanying drawings.

- 10 This invention relates to an improved rotary valve for internal combustion engines, and has for its primary object to provide a simple and efficient water cooled valve of this type.
- 15 It is a more particular object of the invention to provide a valve head for the several engine cylinders, preferably cast *en bloc*, improved means for mounting and retaining the rotary valve members in said head, and
- 20 means for distributing a suitable lubricating oil upon the peripheral surfaces of the rotary valves.

It is a further general object of my invention to provide a valve of the type above referred to which is simple in its construction, reliable and effective in practical use and which may be manufactured and used in connection with internal combustion engines of various construction without necessitating any material modifications therein.

With the above and other objects in view the invention consists in the combination, construction, and relative arrangement of the several parts as will be hereinafter more 35 fully described and subsequently pointed out in the appended claims.

In the accompanying drawings wherein I have illustrated the preferred embodiment of the invention and wherein similar reference characters denote corresponding parts throughout the several views;

Figure 1 is a side elevation of the valve head illustrating the intake and exhaust connections to the several rotary valves;

Fig. 2 is an enlarged fragmentary sectional view through the valve head showing the mounting and arrangement of one of the valves therein;

Fig. 3 is a section taken on the line 3—3 50 of Fig. 2;

Fig. 4 is a detail perspective view of one of the rotary valves; and

Fig. 5 is a similar view of one of the valve bushings.

Referring in detail to the drawing 55 5 designates the several cylinders of an internal

combustion engine which, as illustrated, are preferably cast *en bloc* and connected at their upper ends by an enlargement 6. 7 designates the valve head which is adapted to be detachably secured upon the upper ends 6 of the engine cylinders by any preferred means. This valve head 7 is rectangular in form and of hollow construction. Equidistantly spaced cylindrical valve casings 8 extend transversely through the head 7 and integrally connect the opposite side walls thereof. These valve casings are spaced from the top wall of the head and integrally connected to the bottom wall 70 thereof. A longitudinal slot or opening 9 extends through this base portion of the valve casing and communicates with the interior thereof. The casing is provided with internal longitudinally extending grooves 75 10 at diametrically opposite points. Within each valve casing a bushing is arranged, said bushing including an outer cylindrical wall 11 and an inner wall 12 concentrically spaced from said outer wall. This inner 80 wall of the bushing is preferably formed in two sections spaced apart to provide a longitudinally extending annular chamber 13, said wall sections being permanently secured to each other at their ends. The bushing walls 11 and 12 are unconnected at one of their ends and the outer wall 11 projects longitudinally beyond the end of the inner wall, said end of the inner cylindrical wall being closed as indicated at 14. The projecting end portion of the outer wall 11 is exteriorly threaded to receive a cap nut 16, the purpose of which will presently appear.

17 designates the rotary valve member which is of tubular form and closed at one 95 end. This valve member is adapted to be engaged over the inner cylindrical wall 12 of the bushing and moved longitudinally between the bushing walls to the position seen in Fig. 3 of the drawing. The inner 100 and outer walls of the bushing are provided with coinciding longitudinally extending slots 18 and 19 respectively which are in registering relation with the slot or opening 9 in the base wall of the valve casing. The 105 bushing is held against rotary movement within the valve casing by means of the longitudinal keys 20 formed on the periphery of the wall 11 at diametrically opposite points, said keys frictionally engaging in 110 the ways or grooves 10 provided in the wall of the valve casing.

The rotary valve member 17 is also provided with a longitudinally extending port 21 in its wall which, in the operation of the valve is adapted to register with the 5 slots or openings in the walls of the bushing and with the opening 9 in the base wall of the valve casing. An axially projecting rod or stem 22 is fixed to the closed end of the rotary valve member, the cap nut 16 being provided with a central opening to receive said stem. When the cap nut is threaded upon the end of the bushing and against the side wall of the head 7, it will be apparent that the rotary valve member 15 is retained within the bushing against axial movement in an outward direction. A crank arm 23 is secured upon the stem 22. Rods operated by cams, eccentrics or other suitable means are connected to the arms 23 20 of the respective rotary valves to actuate said valves in timed relation. As this operating means for the rotary valves constitutes no part of the present invention, it is not herein illustrated in detail.

25 Each of the rotary valves 17 is further provided at a point diametrically opposite the port 21 with a longitudinally extending slot 24. A suitable lubricating oil is supplied to the slots 24 of the valves through 30 the medium of a pipe or conduit 25 extending through the head 7 and having communication with ports 26 formed in the top wall of each of the valve casings 8. It will be understood that an intake and exhaust 35 valve constructed and mounted in the manner above explained is provided for each of the engine cylinders. The valves 17 at one of their ends are open for communication with the intake and exhaust connections 40 designated 27 and 28 respectively which are secured to the side of the valve head 7. It will be noted from reference to Fig. 1 that the exhaust manifold 28 is disposed immediately above and in contact with the intake manifold 27 so that the gas charge 45 will be highly heated and vaporized in its passage through the manifold 27 to the several engine cylinders.

50 A radially extending opening 29 extends from the chamber 13 at the connected ends of the bushing walls 11 and 12 outwardly to the periphery of the bushing and a duct or passage 30 extends through the top wall of the valve casing 7 and forms in effect a 55 continuation of the opening 29. Thus the water in the hollow head 7 will flow through the passage 30 and opening 29 and fill the chamber 13 to effectively cool the inner wall of the valve bushing.

60 From the foregoing description taken in connection with the accompanying drawing, the construction, manner of operation and several advantages of my improved valve will be clearly and fully understood. Water 65 is continuously circulated through the head

7, entering the head at one end thereof through the pipe 31 and leaving the head at its opposite end through the pipe 32. This water flowing over and around the several casings 8, and through the inner walls thereof, cools the rotary valves mounted in said casings and eliminates the possibility of preignition of the gaseous charge. The several valves are rotated at proper times so as to bring the ports 19 thereof in registration 75 with the openings 9 to exhaust the burned gases from the several cylinders and admit a fresh charge thereto. In the operation of the device, the lubricating oil is continuously supplied to the several valve members and 80 in the actuation of the valve member, this oil passes through the slot 24 therein for distribution over the inner face of the outer wall 11 and the outer face of the inner wall 12 of the bushing and upon the contacting 85 surfaces of the rotary valve. Thus the valves will operate with a minimum of friction so that the resurfacing or regrounding of the same will be avoided. The valves may however, be very easily and quickly removed from the valve head or reinserted in their operative positions. The device as a whole is of relatively simple construction, and the several parts may be manufactured at small cost and installed for use in connection with various types of internal combustion engines without necessitating any material alterations in the latter. While I have herein shown and described the preferred construction and arrangement of the 90 several elements employed, it is to be understood that the same are susceptible of considerable modifications, and I therefore reserve the privilege of adopting all such legitimate changes as may be fairly embodied 95 within the spirit and scope of the invention as claimed.

Having thus fully described my invention, what I claim and desire to secure by Letters Patent is:—

1. In a valve mechanism for internal combustion engines, a hollow head common to all of the engine cylinders having water inlet and outlet connections at its opposite ends, a plurality of valve casings extending 115 transversely through said head, said head having ports opening through one wall thereof and communicating with the respective valve casings, a double walled bushing fitted in each of the valve casings, the inner bushing wall having a water receiving chamber in communication at one of its ends with said hollow head, and a rotary valve mounted between the walls of said bushing, said valve and the bushing walls 120 also having ports to register with said first named ports.

2. In a valve for internal combustion engines, a valve casing, a double walled bushing fitted within said casing, a rotary valve 130

member engaged between the walls of the bushing, said bushing walls and the valve member having ports adapted to register in the operation of the valve, the inner wall of the bushing being chambered, and means for supplying a cooling medium to said chamber.

3. In a valve for internal combustion engines, a hollow valve head having a casing 10 extending transversely therethrough, a bushing fitted within the casing and having inner and outer spaced walls, a rotary valve member disposed between the walls of the bushing, said walls and the valve member 15 having ports adapted to register in the op-

eration of the valve, the inner wall of the bushing being chambered, and means for circulating water through said head, said bushing and the wall of the valve casing having registering passages affording communication between the hollow head and the chamber in the bushing wall whereby water is supplied to the latter.

In testimony whereof I hereunto affix my signature in the presence of two witnesses. 25

ELMER A. EKLUND.
